UNITED STATES PATENT OFFICE.

THOMAS HENRY MARTEN, OF TORONTO, ONTARIO, CANADA.

DAVIT FOR SHIPS' LIFE-BOATS.

1,319,353.

Specification of Letters Patent.

Patented Oct. 21, 1919.

Application filed March 15, 1918. Serial No. 222,710.

To all whom it may concern:

Be it known that I, THOMAS HENRY MARTEN, a subject of the King of Great Britain, and resident of the city of Toronto, 5 county of York, Province of Ontario, in the Dominion of Canada, have invented certain new and useful Improvements in Davits for Ships' Life-Boats, as described in the following specification and illustrated 10 in the accompanying drawings, that form part of the same.

The principal objects of this invention are, to provide an improved means for operating life boat davits particularly of the 15 type in which the boom swings in a vertical plane upon a fixed pivot and which will not be detrimentally affected by bending stresses caused by deflections of the boom or of other parts of the davit structure and in 20 which the actuating members are effectively protected from injury.

A further and important object is to devise a structure in which the member operatively connecting the boom with the 25 actuating member imparts stability to said actuating member and maintains the latter free of bending stresses and further limits the movement of the boom in the event of the actuating member failing.

30 The principal feature of the invention consists in the novel construction and arrangement of parts, whereby the davit boom is connected intermediate of its ends to a rigid support by a telescopic member, the outer portion of which is actuated by a rotatable screw spindle mounted on the rigid support and flexibly connected with said outer telescopic member.

In the drawings, Figure 1 is a side elevational view of my improved form of davit showing the position of the parts when the boom is in the extreme inboard position.

40 Fig. 2 is a side elevational view showing the parts in their extended position when the boom is swung outboard.

Fig. 3 is an enlarged sectional detail view of the means for operating the davit boom.

45 Fig. 4 is a detail plan view of the screw spindle showing the pivotal support for the operating spindle.

The type of the davit herein shown is

that in which the boom 1 is pivotally supported at its foot to swing in a vertical plane, the pivot pin 2 being mounted in the base 3 secured to the deck of the ship. 55

A frame 4 connected with the base 3 and secured to the deck extends in an upward inboard direction and is here shown formed with a pair of horizontally arranged lugs 5.

5 A pin 6 is pivotally mounted in the lugs 5 and is formed with a head 7 bearing upon the upper lug and said head is bifurcated at its upper end.

60 A rod 8 is pivotally mounted on the pin 9 extending transversely through the upper 65 bifurcated end of the head 7 and forms one of the portions of the telescopic boom support.

65 A sleeve member 10 slidably encircles the rod 8, its inboard end having a substantial 70 length of bearing upon the rod and the remaining portion 11 thereof is of greater inside diameter than the diameter of the rod 8.

70 12 is a collar secured to the outer end of the rod 8 and slidably engaging the enlarged inner portion 11 of the sleeve 10 and said collar abuts the bearing end of the sleeve when the member is extended to its maximum position.

75 The outer end of the sleeve 10 is formed 80 with a shoulder 13 and encircles said sleeve adjacent to and abutting said shoulder is a shackle member 14 which is provided with a jaw end 15, the outer end of which is secured to the pin 16 extending through the 85 davit boom. The shackle member 14 is secured in place upon the sleeve 10 by suitable set screws 17.

80 A collar 19 encircles the inboard end of the sleeve 10 and is rigidly secured thereto 90 in any suitable manner, set screws 20 being shown extending through said collar into the sleeve.

90 The collar 19 is formed with a pair of 95 downwardly projecting lugs 21 which are spaced apart and formed with openings 22 therethrough arranged in axial alinement and preferably parallel to the sleeve.

95 A screw spindle 23 is journaled at one end in a housing 24 and extends through 100 the bifurcated portion of the pivotal head and through the openings 22 and is thread-

ed through a nut 25 which is arranged in the space 26 and loosely engages the lugs 21 of the collar 19.

The housing is pivotally supported upon 5 the pins 27 rigidly mounted in the head 7 by the ring bolts 28. This pivotal support for the spindle allows it to swing so that it maintains its relation substantially parallel with the telescoping boom connection 10 as said boom connection swings upon its pivotal support on the head 7.

A tube 29 is suspended from the sleeve 10 by the members 30 and incloses the spindle and forms a guide for the spindle which 15 is provided with a collar 31 sliding therein.

In the operation of this device the spindle 23 is rotated by means of the operating crank 32 secured at the inner end and the rotation of the spindle in one direction 20 causes the nut 25 to travel outwardly pushing the sleeve 10 outwardly upon the rod 8 until the collar on the end of the rod engages the shoulder 33 at the inboard end of the sleeve.

25 The independent pivotal arrangement of the screw spindle and the manner of connection with the telescopic members obviates any binding action upon the spindle through normal distortions of the telescopic members. Further, the operating members are supported at the inner end upon a vertical pivot and a universal pivotal support for the operating members is provided.

30 The structure of the telescopic members is such that in the event of failure of the screw spindle through any cause the outward swing of the boom is limited by the engagement of the collar 12 with the shoulder 33 in the sleeve 10.

40 A davit such as described will operate very freely and the parts are of very simple construction.

What I claim as my invention is:—

1. In a davit for ships' life boats, the combination with the boom and a rigid support, 45 of a telescopic member having one end connected to the boom intermediate of its ends and the other end connected to said rigid support, and a screw spindle mounted on said rigid support and operatively connected with the operating portion of said telescopic member.

2. In a davit for ships' life boats, the combination with the boom and a rigid support, 55 of a telescopic member having one end connected to the boom intermediate of its ends and the other end connected to said rigid support, and a screw spindle pivotally mounted on said rigid support and flexibly connected with the operating portion of said telescopic member.

3. In a davit for ships' life boats, the combination with the boom and a rigid support, 60 of a telescopic member having one end con-

nected to the boom intermediate of its ends 65 and the other end pivotally connected to said rigid support, and a screw spindle pivotally supported from said rigid support and flexibly connected with the operating portion of said telescopic member. 70

4. In a davit for ships' life boats, the combination with the boom and a rigid frame structure, of a tubular member pivotally connected to said boom intermediate of its ends, 75 a pivot head secured to said frame, a rod pivotally connected to said pivot head and telescoping into said tubular member, and a screw spindle pivotally mounted on said pivot head and flexibly connected with said tubular member. 80

5. In a davit for ships' life boats, the combination with a boom and a rigid frame, of a tubular member pivotally connected to the boom intermediate of its ends, a rod 85 telescopically arranged in said tube and connected to said rigid frame, a collar member secured to the inner end of said tubular member and having a pair of lugs projecting from one side thereof, said lugs having openings therethrough, a journal pivotally mounted on said rigid frame, a screw spindle supported in said journal and extending through the openings in the lugs of the collar member carried by said tubular member, and a nut threaded on said spindle and 95 loosely arranged between said lugs.

6. In a davit for ships' life boats, the combination with the boom and a rigid frame, a vertically arranged pivot head supported in said frame, a journal pivotally supported 100 upon transversely arranged pivots mounted on said pivot head, a screw spindle supported in said journal, a rod pivotally secured to said pivot head above said spindle, a sleeve telescopically mounted upon said 105 rod and pivotally connected at its outer end to the boom, and a nut threaded upon said spindle and engaging said sleeve.

7. In a davit for ships' life boats, the combination with the boom and a rigid support, 110 of a pair of telescopically engaging members one of which is connected to the boom and the other is connected to said support, said members having positive stops to limit their outward movement, and a screw 115 spindle mounted on the rigid support and operatively connected with the operating telescoping member.

8. In a davit for ships' life boats, the combination with the boom and a rigid support, 120 of a telescopic member having one end connected to the boom intermediate of its ends and the other end connected to said rigid support, a screw spindle pivotally mounted on said rigid support and operatively connected with the operating portion of said telescopic member, and a guide supporting 125 the outer end of said spindle.

9. In a davit for ships' life boats, the combination with the boom and a rigid support, of a telescopic member having one end connected to the boom intermediate of its ends and the other end connected to said rigid support, a screw spindle pivotally mounted on said rigid support and operatively con-

nected with the operating portion of said telescopic member, and a tubular guide supported from the telescopic member and arranged parallel thereto and inclosing said screw spindle.

THOMAS HENRY MARTEN.
